US00D567107S

(12) **United States Design Patent** (10) Patent No.: **US D567,107 S**
Crawford et al. (45) Date of Patent: ** *Apr. 22, 2008

(54) **COMBINED CONTAINER AND PUMP**

(75) Inventors: **John C. Crawford**, Mahopac, NY (US); **Roland Charriez**, Mohegan Lake, NY (US)

(73) Assignee: **Colgate-Palmolive**, New York, NY (US)

(*) Notice: This patent is subject to a terminal disclaimer.

(**) Term: **14 Years**

(21) Appl. No.: **29/278,215**

(22) Filed: **Mar. 22, 2007**

(51) LOC (8) Cl. **09-01**

(52) U.S. Cl. **D9/682**

(58) Field of Classification Search D9/682-695, D9/516-575, 447-450; 215/384-386; 220/669, 220/675; 222/321.7, 321.8, 321.9, 372, 373, 222/379, 383.1, 384-386, 398, 400.7, 400.8, 222/401, 402, 402.1, 402.11, 631

See application file for complete search history.

(57) **CLAIM**

The ornamental design for a combined container and pump, as shown and described.

DESCRIPTION

FIG. 1 is a perspective view of the combined container and pump showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

1 Claim, 6 Drawing Sheets
